UNITED STATES PATENT OFFICE

166,718

NOVELTY BRACELET OR SIMILAR ARTICLE

Milton M. Schrager, Far Rockaway, N. Y.

Application November 19, 1951, Serial No. 17,464

Term of patent 7 years

(Cl. D34—15)

To all whom it may concern:

Be it known that I, Milton M. Schrager, a citizen of the United States of America, residing in Far Rockaway, county of Queens, and State of New York, have invented a new, original, and ornamental Design for a Novelty Bracelet or Similar Article, of which the following is a specification, reference being had to the accompanying drawing, forming part thereof,

Fig. 1 is a front view of a novelty bracelet or similar article, showing my new design;

Fig. 2 is an edge view thereof; and

Fig. 3 is a perspective view of the novelty bracelet or similar article on a larger scale.

The dominant feature of my design resides in the portions shown in solid lines.

The drawing figures are shaded to indicate transparency.

I claim:

The ornamental design for a novelty bracelet or similar article, substantially as shown and described.

MILTON M. SCHRAGER.
